UNITED STATES PATENT OFFICE.

HENRY W. PARTON, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 14,243, dated August 28, 1883.
Application filed May 22, 1883. Term of patent 3½ years.

To all whom it may concern:

Be it known that I, HENRY W. PARTON, of Yonkers, Westchester county, New York, have invented a new and original Design for Carpets, of which the following is a specification.

The accompanying photograph illustrates my new design for carpets.

This invention relates to a new design for carpets, oil-cloths, and analogous fabrics; and it consists of the new ornamentation of parts hereinafter more fully pointed out.

The figure A in the photograph represents the contour of a hill, behind which are flashes or streaks B of light, by which the hill is thrown in prominent view. On this representation A of a hill appears to grow a shrub

or tree, C, and on the slope of the hill is a floral group, D. Below the hill is the representation F of a shrub. The lower part of the carpet, where it indicates the foot of the hill, has streaks a a of light, and leaves b, and floral ornaments d, all as shown. The shrub C has clusters of fruit, which have a peculiar streaky surface, as shown.

I claim—

The design for carpets, consisting of the figures A B C D F a b d e, substantially as shown.

HENRY W. PARTON.
